UNITED STATES PATENT OFFICE.

PETER D. KEENAN, OF SAN FRANCISCO, CALIFORNIA.

NURSING-BOTTLE BRACKET.

1,232,690.

Specification of Letters Patent. Patented July 10, 1917.

Application filed July 27, 1914. Serial No. 853,301.

To all whom it may concern:

Be it known that I, PETER D. KEENAN, a citizen of the United States, residing in the city and county of San Francisco and State of California, have invented new and useful Improvements in Nursing-Bottle Brackets, of which the following is a specification.

This invention relates to a device for holding nursing bottles in convenient position to an infant.

The particular object of the present invention is to provide a bracket for ready attachment to a chair, table, crib, or other convenient support, and upon which a nursing bottle may be readily and safely mounted so as to be protected against injury by falling to the floor or other adjacent surface and being broken when released by the infant.

The invention consists of the parts and the construction and combination of parts as hereinafter more fully described and claimed, having reference to the accompanying drawing, in which—

The figure is a perspective view of the device, showing a nursing bottle adjusted in position thereon.

2 indicates a substantial U-shaped bracket or arm, having a threaded boss 3 for the reception of a thumb-screw 5 with a swivel 30 washer 6 adapted to be forced up against a convenient support 7, as the arm of a chair or rail of a crib, etc.

Upon the bracket 2 is formed an extension 8 engageable with the supporting member 35 upon which the bracket may be mounted. On the opposite and upper member of the bracket 2 is a tubular threaded arm 9 for receiving a threaded post 10, upon which is mounted a lock nut 11 whereby the post 10 40 may be locked in suitable adjusted position in the tube 9 of the bracket.

Pivoted or otherwise suitably connected to the upper end of the threaded post 10 is a curved seat or receiver 12 upon which a nursing bottle, as 13, may be placed and held firmly thereupon by a spring 14 suitably connected to the upper portion of the seat 12; the spring 14 yielding to receive the bottle 13 when the latter is inserted and operating to securely hold the bottle against abnormal movements upon the seat 12. Thus I have provided a simple, practicable device adjustable to meet the conditions that may arise in use and which conveniently and effectually holds a nursing bottle within reach 55 and use of an infant.

Having thus described my invention, what I claim and desire to secure by Letters Patent is—

A holder for nursing bottles, composed of 60 a horizontal seat formed of a metal plate bent so as to be curved in cross-section to conformably receive the bottle on its side therein and having each of its ends free, a single spring connected at its ends to the 65 sides of said plate at points central of the length of said sides so that said spring extends across the seat, said seat being comparatively short so that a bottle when placed therein will have each of its ends extending 70 beyond the respective ends of the seat so that the bottle will be permitted to be slightly rocked either upwardly or downwardly with the rear and front ends of the plate respectively as fulcra.

In testimony whereof I have hereunto set my hand in the presence of two subscribing witnesses.

PETER D. KEENAN.
